UNITED STATES PATENT OFFICE.

BARNEY A. KNUDSON, OF SANTA ANA, CALIFORNIA.

FORM FOR CONCRETE WALLS.

1,414,287.

Specification of Letters Patent. Patented Apr. 25, 1922.

Application filed August 17, 1920. Serial No. 404,217.

To all whom it may concern:

Be it known that I, BARNEY A. KNUDSON, a citizen of the United States, residing at Santa Ana, in the county of Orange and State of California, have invented new and useful Improvements in Forms for Concrete Walls, of which the following is a specification.

It is the object of the present invention to 10 provide a form for concrete walls which is of extremely simple and inexpensive construction and which may be readily placed in and removed from operative position.

It is a further object of the invention to 15 provide a form by the use of which a unitary hollow wall construction may be formed.

The invention will be readily understood from the following description of the accompanying drawings, in which—

20 Figure 1 is a side elevation showing the portion of a form in operative position.

Fig. 2 is a plan view showing a portion of a form and the wall formed thereby.

Fig. 3 is a transverse section on the line 25 3—3 of Fig. 1.

Fig. 4 is a longitudinal section through one of the core members.

Fig. 5 is a plan view of the same partly broken away.

30 Fig. 6 is a plan view of a portion of a form showing a somewhat modified method of using the same.

Fig. 7 is a transverse section on the line 7—7 of Fig. 6.

35 In the drawings the improved form is shown in position for constructing the course A of a partially completed concrete wall B. It will be understood that the wall is progressively built up of said courses, the forms 40 being mounted upon the preceding course of the wall for building up the next upper course.

In practice a sufficient number of form sections may be positioned one beyond the other to form a complete course of the wall at one operation, or if the supply of form sections is limited a portion of a course may be constructed at one operation and some of the forms then removed and repositioned 45 with relation to the portion of the course already formed in order to complete the formation of the course. This latter method of using the form construction is exemplified in Figs. 6 and 7.

50 The form consists of a plurality of frame members such as clearly shown in Fig. 3 and

which are mounted in longitudinally spaced relation along a wall so as to form means for supporting side boards extending along the sides of the wall and projecting upwardly 60 therefrom so as to form a space into which the concrete for forming the new course may be poured.

Each of the frame members comprises side uprights each of which consists of spaced 65 members 1 and 2. A support 3 is secured across the lower ends of members 1 and 2 and is adapted to abut against the wall B so as to position the uprights in spaced relation from said wall. The side boards 4 are 70 supported in upright position upon supports 3 between the portion of the wall already formed and the uprights of the frame members. Hooks 45 are pivoted upon the uprights of the frame members for engaging 75 the side boards to retain the latter in position. Bolts 46 also project laterally at the ends of certain of the side boards adapted to be arranged at corners of the form construction. These bolts are engaged by nuts 80 47 for retaining the corner side boards in position relative to one another. The side boards thus form a space 5 into which the concrete is poured.

The side uprights are connected intermediate of their ends by a cross brace 6 received between the spaced members 1 and 2 of the respective side uprights. The ends of the cross brace are, preferably, provided with apertures 7 spaced along the brace so 85 that screw bolts 8 may be inserted through apertures 9 in the uprights 1 and 2 and through any one of the apertures 7 at the respective ends of the cross brace in order to space the side uprights apart various distances for forming walls of different thicknesses. 95

Provision is made for drawing together or forcing apart the upper ends of the side uprights in order to swing the latter upon the 100 pivots formed by bolts 8 for either forcing the lower ends of the side uprights and supports 3 into clamping engagement upon wall B or spreading apart the lower ends of the side uprights in order that they may be removed from the wall.

As an instance of this arrangement a turnbuckle 10 is arranged to engage the threaded rods 11 and 12 projecting from the respective ends of the turnbuckle. One of said rods 110 shown at 11 is provided with an outer end through which is formed a plurality of

spaced apertures 13. This end of the rod is adapted to be received between the spaced members 1 and 2 of one of the side uprights with a screw bolt 14 received through suitable apertures 15 in the spaced members and through any one of the apertures 13. The rod 12 is provided with an end 17 received between spaced members 1 and 2 of the opposite side upright, and said rod is provided 10 with a plurality of spaced notches 16, any one of which is arranged to be received over screw bolt 14 received through apertures 15 of the spaced members of said side upright.

15 If desired additional bracing means may be provided between the side uprights. As an instance of this arrangement bars 18 and 19 overlapping one another and longitudinally adjustable with relation to one another 20 by means of aligned slots 20 provided therein and arranged to receive a screw bolt 21, are secured at their respective outer ends to the side uprights. The bar 18 may be secured to one of the side uprights by passing the 25 outer end of the bar between the spaced members 1 and 2 comprising said side upright and extending bolt 14 through a suitable aperture in said bar. The bar 19 may be similarly received between the spaced members 30 forming the opposite side upright with the bolt 8 connecting said spaced members received through a suitable aperture in the bar.

Core members are, preferably, provided 35 for use in connection with the form as thus described, said core members being arranged to form a hollow wall construction. These core members are shown as cylindrical members placed in upright position in space 5, 40 as clearly shown in Figs. 2 and 3. Each of the core members consists of a plate 23 curved upon itself with its ends overlapping as shown at 24-25 in order to provide a cylindrical core construction. A top 26 fits 45 over this core construction and an annular depending flange 27 of the top is bolted as shown at 28 to one end of the plate 23. A handle 29 is provided upon the top so that by twisting the handle the top and the end 50 of plate 23 secured thereto may be shifted with relation to the opposite end 24 of the plate for decreasing the diameter of the cylinder forming the core. By this arrangement the core may be either expanded or 55 contracted in order to permit of its insertion and removal from the wall when formed.

A lock is, preferably, provided for retaining the core construction in expanded position, said lock comprising a pin 30 received 60 through aligned openings 31-32 in the overlapping ends 24-25. This pin is mounted upon a bar 33 pivoted at 34 to the inner end of the core construction so that by swinging said bar the pin may be inserted in or removed from the aligned openings. The bar

34, is preferably, actuated by a lever 35 extending upwardly through the top of the core construction.

When the form, as thus constructed, is employed for forming portions of a course 70 the ends of the fragmentary form are, preferably, closed by end boards 37 received between the spaced members 1 and 2 of the side uprights of the frame members at the ends of the fragmentary form. These end boards 75 rest upon the supports 3 of the side uprights in alignment with the side boards 4. This arrangement is shown in Figs. 6 and 7. A portion of a course having been poured in the fragmentary form thus provided the 80 frame members and side boards forming said fragmentary form may be removed and reset in position beyond the end of the fragmentary form for the next portion of the course of 85 the structure.

It will be obvious that any suitable tie rods and reinforcing bars may be employed in connection with the improved form so as to be embedded in the concrete construction. 90 In Fig. 2 is shown an arrangement of horizontal tie rods comprising the longitudinally extending rods 38 connected by cross rod 39. Vertical tie rods employed in connection therewith are also shown at 40. 95

It will be observed that the form construction provides for the building of a unitary concrete wall having hollow spaces within the same thus obtaining in a single structure the advantages of both a hollow wall construction and of a unitary wall construction. 100 Various changes may be made without departing from the spirit of the invention as claimed.

What is claimed is:

1. A form for concrete walls comprising a pair of spaced upright members for each side, a support secured across the lower ends and inner faces of each pair of upright members, side boards resting upon the supports, hooks pivoted to the upright members and extending over the upper edges of the side boards to hold the side boards in position, a cross brace between the upright members of each pair above the hooks and having a plurality of apertures, screw bolts inserted through the pairs of upright members and through desired ones of the apertures, a turnbuckle, rods threaded into the turnbuckle, one of said rods having a plurality of spaced apertures and the other of said rods having a plurality of spaced notches, and bolts inserted through the upper ends of the pairs of uprights for engagement by the turnbuckle rods so that by setting the cross brace and turnbuckle rods to the desired width of wall the side boards may be tightened upon the wall by manipulating the turnbuckle one way and loosened by manipulating the turnbuckle the other way. 120 125 130

- .2. A form for concrete walls comprising
a pair of spaced upright members for each
side, a support secured across the lower ends
and inner faces of each pair of upright mem-
bers, side boards resting upon the supports,
hooks pivoted to the upright members and
extending over the upper edges of the side
boards to hold the side boards in position,
a cross brace between the upright members
10 of each pair above the hooks and having a
plurality of apertures, screw bolts inserted
through the pairs of upright members and
through desired ones of the apertures, a turn-
buckle, rods threaded into the turnbuckle,
15 one of said rods having a plurality of spaced
apertures and the other of said rods having
a plurality of spaced notches, bolts inserted
through the upper ends of the pairs of up-
- rights for engagement by the turnbuckle
rods so that by setting the cross brace and 20
turnbuckle rods to the desired width of wall
the side boards may be tightened upon the
wall by manipulating the turnbuckle one
way and loosened by manipulating the turn-
buckle the other way, bars overlapping at 25
their inner ends and having alined slots, and
a clamping bolt in the alined slots one end
of one bar being mounted upon one of the
bolts holding the cross bar, and the opposite
end of the other bar being mounted upon the 30
opposite one of the bolts holding the turn-
buckle rods so as to form an adjustable
diagonal brace.

In testimony whereof I have signed my
name to this specification.

BARNEY A. KNUDSON.
